UNITED STATES PATENT OFFICE

94,342

DESIGN FOR A SHOE

Ernest C. Doring, Quincy, Mass., assignor to
Scholnick Shoe Co., Jamaica Plain, Mass., a cor-
poration of Massachusetts

Application September 7, 1934, Serial No. 53,221

Term of patent 3½ years

To all whom it may concern:

Be it known that I, Ernest C. Doring, a citizen of the United States, residing at Quincy, in the county of Norfolk and Commonwealth of Massachusetts, have invented a new, original, and ornamental Design for a Shoe, of which the following is a specification, reference being had to the accompanying drawing, forming a part thereof, in which

Fig. 1 is a view in perspective of a left shoe showing my new design, as seen from the right-hand side;

Fig. 2 is a similar view of the shoe as seen from the left-hand side; and

Fig. 3 is a detail view, on an enlarged scale, of the ornament covering the gore.

I claim:

The ornamental design for a shoe substantially as shown and described.

In testimony whereof, I have affixed my signature hereto.

ERNEST C. DORING.
